LUBRICATING UNIT

Clyde E. Wright, Elyria, Ohio, assignor to The Ridge
Tool Company, Elyria, Ohio

Application February 24, 1955, Serial No. 34,685

Term of patent 14 years

(Cl. D46—1)

Fig. 2

Fig. 1

Fig. 1 is a side elevational view of the lubricating unit embodying my new design; and

Fig. 2 is a top plan view.

The side of the lubricating unit not shown is the same as the side illustrated in the drawing.

I claim:

The ornamental design for a lubricating unit, as shown and described.
